PNEUMATICALLY OPERATED RAILROAD GATE

Filed Sept. 1, 1923

2 Sheets-Sheet 2

UNITED STATES PATENT OFFICE.

PATRICK P. O'CONNELL, OF ST. JAMES, MINNESOTA.

PNEUMATICALLY-OPERATED RAILROAD GATE.

Application filed September 1, 1923. Serial No. 660,489.

To all whom it may concern:

Be it known that I, PATRICK P. O'CONNELL, a citizen of the United States, residing at St. James, in the county of Watonwan and State of Minnesota, have invented certain new and useful Improvements in Pneumatically-Operated Railroad Gates, of which the following is a specification.

In carrying out the present invention it is my purpose to provide a pneumatically operated railroad gate which will be found especially useful at highway crossings, and which will be constructed in such manner that as the train approaches the crossing the wheels of the train may operate an air pump to deliver compressed air to an air motor connected with the gate, whereby the gate will be lowered, and as the train leaves the crossing the air in the motor may be released, so that the gate may return to normal position, thereby removing the obstruction from the highway so that traffic may proceed thereover.

It is also my purpose to provide a train operated pneumatic mechanism for controlling railroad gates at highway crossings which may be used with both a single and double track railway lines, and which will embrace the desired features of simplicity, efficiency and durability, coupled with cheapness of cost in manufacture, installation and maintenance.

With the above recited objects in view, and others of a similar nature, the invention resides in the construction, combination and arrangement of parts set forth in and falling within the scope of the appended claims.

In the accompanying drawings:

Figure 1 is a view in side elevation showing my invention as applied to a single track railroad.

Figure 2 is a top plan view showing the wheel operated pump or compressor mechanism.

Figure 3 is a fragmentary sectional view showing the gate operated motor.

Figure 4 is a fragmentary side elevation showing the release mechanism.

Figure 5 is a detail sectional view showing the connection between the motor and the gate.

Figure 6 is a diagrammatic side elevation showing the construction for a double track railroad.

Figure 7 is a longitudinal sectional view through the automatic valve that is used

with the double track mechanism.

Referring now to the drawings in detail, and particularly to the form of my invention illustrated in Figures 1 to 5 inclusive, 60 1 designates a railroad right of way, while 2 indicates a highway that intersects the railroad right of way. Upon one side of the highway adjacent to the track is a standard or post 3, and at the other side of the highway adjacent to the track is a keeper 4. Pivoted between its ends upon the upper end of the post 3 is a gate 5 having a relatively long arm that is designed to extend across the highway when the gate is in 70 lowered position and a relatively short arm 6 equipped with a counter-weight 7 which acts to restore the gate to normal position and maintain the same in such position. Fixed to the upper end of the post 3 is a 75 toothed segment 8 with which meshes a pinion 9 journaled upon the gate and provided with a crank pin which in turn is connected with one end of a connecting rod 10, the other end of such rod being connected with a crank arm 11 pivoted upon a pin 12 carried by the relatively long arm of the gate adjacent to the outer end of such arm. This crank arm 11 is integral with a rest post 13. As long as the gate 80 is in upright or open position, the pinion 9 is at the upper end of the segment 8 and the rest post 13 lies substantially alongside of the gate. When, however, the gate is lowered to horizontal or closed position, as 85 shown by the dotted lines in Figure 1 of the drawings, the pinion 9 moves over the rack or segment 8, thereby operating the rod 10 to swing the crank arm 11 about the pivot pin 12, thereby swinging the rest pin 90 13 to a position at right angles to the gate, so as to engage the ground and assist in supporting the outer extremity of the gate, as shown by the dotted lines in Figure 1 of the drawings.

The relatively short arm 6 of the gate immediately below its pivotal connection with the post 3 is formed with an opening in which is journaled a pin 14 that carries an eye element 15 through which extends 105 one end of a rod 16. The other end of the rod 16 is pivotally connected, as at 17, with the upper end of a piston rod 18 of an air motor 19. In the present instance this air motor 19 comprises a cylinder 20 that is 110 fixed upon a bracket 21 secured to the post 3 adjacent to its lower end, and a piston

21 within the cylinder 20 connected to the inner end of the rod 18. Fastened to the rod 16 adjacent to its lower end is a collar 22, and interposed between the collar 22 and the eye element 15 is a coiled expansion spring 23 that forms a yieldable connection between the rod 16 and the gate and permits the motor to transmit power to the gate without shock or jar.

10 As long as the piston 21 is at the lower end of the cylinder 20, the gate is maintained in open position under the action of the counter-weight 7, while when air is admitted to the lower end of the cylinder 20 15 the piston 21 is forced upwardly within the cylinder and motion is transmitted through the piston rod 18 and the rod 16 to the gate, with the result that the gate is swung to closed position, as shown by the dotted lines 20 in Figure 1 of the drawings. As soon as the air pressure is released from the cylinder 20, the counter-weight 7 re-acts to restore the gate to open position.

In advance of the approach to the crossing, I employ a compressor 24 arranged alongside of the track and comprising, in the present instance, a vertical cylinder 25, a piston 26 within the cylinder 25 and a piston rod 27 connected to the piston 26 and 30 extending upwardly through the upper end of the cylinder 25. This piston rod 27 is connected with one end of a rocker arm 28 that is arranged at right angles to the adjacent line of rails of the track, as clearly 35 shown in Figure 2 of the drawings. The other end of the rocker 28 is bent at right angles to itself, and journaled in bearings 29 carried by a plate 30 fastened to the adjacent line of rails. The rocker arm 28 extends 40 through an eye 31 formed in the outer end of a treadle arm 32. The major portion of this treadle arm 32 lies alongside of the rails, as shown in Figure 2 of the drawings, and the other end thereof is pivoted upon a 45 vertical pivot pin 33 carried by a plate 34 fastened to the adjacent line of rails, a leaf spring 36 having one end fastened to the plate 34 and the other end bearing against the treadle arm 32, so as to hold the same 50 normally against the adjacent line of rails. As a train approaches the highway, the wheels thereof ride over the treadle arm 32 and depress the latter, and as the wheel flanges engage the treadle arm, the latter 55 swings outwardly about the pivot pin 33 against the action of the spring 36. In the downward movement of the treadle arm 32 motion is transmitted through the eye 31 to the rocker arm 28, thereby forcing the piston 26 downwardly within the cylinder 25. The cylinder 25 is connected by a pipe line 37 with the lower end of the motor cylinder 20 and in this pipe line is a check valve 38, so that as the piston 26 moves downwardly 60 within the cylinder 25, air is forced through

the pipe line 37 into the motor 19, thereby operating the motor to lower the gate, as previously described, the check valve 38 acting to prevent the return of the air to the compressor after the treadle arm 32 is relieved of the influence of the car wheels.

At the other side of the crossing is an air release mechanism shown in detail in Figure 4 of the drawings. This air release mechanism embodies a pipe line 39 that 75 leads from the lower end of the motor cylinder 20 and the end of the pipe line 39 remote from the crossing is provided with a release valve 40, which, when opened, releases the air from the motor cylinder, so 80 that the gate may return to its open position. This valve 40 is normally closed and is provided with a crank arm 41 connected through a pin and slot connection 42 with an actuating arm 43 which is connected to 85 one end of a treadle 44 arranged alongside of one line of rails of the track. The other end of this treadle 44 is pivoted, as at 45, for universal movement to a bracket 46 carried by an adjacent tie. The end of the 90 treadle 44 connected with the actuating arm 43 is also connected with an appropriate form of dash pot 47, so that the movement of the treadle 44 to normal position may be retarded. After the train has left the crossing, the wheels thereof engage the treadle bar 44, thereby depressing the actuating arm 43, with the result that the release valve 40 is opened, so as to permit the gate to return 95 to normal position.

In the construction shown in Figures 6 and 7 of the drawings, the motor 19 at its lower end is connected by branch pipes 48-48 with ports 49-49, respectively, formed in a cylinder 50 adjacent to the ends 105 of such cylinder. Within this cylinder 50 is a double piston valve comprising piston heads 51-51 having their confronting sides equipped respectively with a piston rod 52 and a hollow rod 53 that telescopes over the rod 52. The hollow rod 53 is formed with an annular flange 54 and interposed between such flange and the piston head carrying the rod 52 is a coiled expansion spring 55 which 110 acts to permit relative movement of the piston heads 51, and at the same time hold such piston heads properly spaced apart under normal conditions. The ends of the cylinder 50 are connected respectively with compressors 56-57, each identical in construction to the compressor hereinbefore described. The compressor 56 is arranged adjacent to the line of rails of one track at one side of the highway crossing, while the compressor 57 is adapted to be arranged at one side of the line of rails of the other track at the other side of the crossing, so that trains 120 moving in both directions over the respective trackways may operate the gate. The pipe line connecting the compressor 56 with 125

100

105

110

115

120

125

130

the automatic valve is provided with a branch pipe line 58 which, in turn, is provided with a release valve mechanism 59 identical in construction to that hereinbefore described with reference to Figures 1 to 5 inclusive, and this release valve mechanism is located adjacent to the same trackway as the compressor 56, but at the opposite side of the crossing. Likewise, the pipe line connecting the compressor 57 with the automatic valve is provided with a branch pipe line 60 which is equipped with an automatic release valve mechanism 61 that is located adjacent to the same trackway, as the compressor 57, but at the other side of the highway crossing.

By means of the construction just described and shown in Figures 6 and 7 it will be seen that the automatic valve will permit either one or both compressors to operate the motor 19, while the automatic release valves 59—61 will release the air from the motor 19 subsequent to the action of the corresponding compressor. Thus, trains passing the crossing in opposite directions may operate the crossing gate independently of each other, and as long as the train is approaching the crossing the gate will be closed, regardless of the release of the air from the motor 19 by a train on the other track having left the crossing or just leaving the crossing.

While I have herein shown and described one preferred form of my invention by way of illustration, I wish it to be understood that I do not limit or confine myself to the precise details of construction herein described and delineated, as modifications and variations may be made within the scope of the claims and without departing from the spirit of my invention.

Having thus described the invention, what is claimed as new is:—

1. In train controlled pneumatic gate mechanism for highway crossings, the combination with a gate mounted for swinging movement from open position to closed position and vice versa, of an air motor connected to said gate for actuating the latter to closed position, a compressor in advance of the approach to the crossing, a pipe line connecting said compressor to said motor and train operated means for actuating said

compressor to force air in the said motor to actuate the latter to lower the gate, a train operated release valve beyond the crossing for releasing the air from said motor, a treadle arm pivoted at one end for swinging movement alongside of the track and adapted to be depressed under the action of the wheels of the train, a connection between the other end of said treadle arm and said release valve, whereby the latter may be opened upon the passage of a train over said treadle arm, said connection comprising an actuating arm connected to said treadle arm, a crank arm connected to said valve, a pin and slot connection between the actuating arm and said crank arm and a dash pot connected to said treadle arm.

2. In a pneumatic gate operating mechanism for use at the intersection of a double track railroad, and a highway crossing, the combination with a gate arranged at the crossing and movable to open and closed position, of an air motor connected to said gate, a train operated air compressor adjacent each trackway at relatively opposite sides of the highway operable by the passage of the train to operate said air motor, train operated air release valve mechanism associated with each compressor and arranged at the relatively opposite side of the highway to release the air from said motor subsequent to the operation of the corresponding compressor, and an automatic valve and shock absorber interposed between said air motor and air compressors having a cylinder, the ends of said cylinder receiving connection from the compressors and the side portion having connection with the air motor, a pair of pistons mounted to reciprocate said cylinder, and means for normally forcing said pistons toward the ends of said cylinder for closing the connections to the air motor, whereby each piston is operated by its respective compressor for moving it toward the other piston to uncover the connections of the air motor to permit the air from the compressor to operate the motor, each compressor operating the motor independently of the other and each release valve also permitting operation of the motor independent of the other.

In testimony whereof I affix my signature.

PATRICK P. O'CONNELL.
